HOSE WINDER OR REEL

Harry G. Neale, Vineland, N. J.

Application February 17, 1939, Serial No. 256,891

4 Claims. (Cl. 242—86)

The present invention relates to hose winders or reels especially, but not exclusively, adapted for use in fire stations or houses with fire hose which is adapted to coil flatwise rather than in cylindrical form. Frequently upon return from a fire the wet hose is in a coil. It is uncoiled and hung up to dry. When dry the hose is recoiled for storage and some of it is uncoiled and loaded onto a truck for future use. Fire hose is of different diameters and is in the form of suitable lengths provided at their ends with coupling elements or couplings.

The principal object of the present invention is to save time and labor in effecting the operations above referred to and to provide a simple, comparatively inexpensive and easily operated reel or winder for that purpose.

Other objects of the invention will appear from the following description at the end of which the invention will be claimed.

Generally stated, the invention comprises a circular turntable mounted from underneath for rotation about a vertical axis and provided on top with a centrally disposed keyway or socket, a handcrank having a shank adapted at its end to detachably engage the keyway or socket in order to rotate the table, a clamp finger having its shank adjustably mounted on the stem of the handcrank for upward and downward movement and adapted to overlie and engage the coupling at the end of a length of hose, and a pair of aligned guide rolls of which one is horizontal and the other is inclined in respect to the first and which are arranged in proximity with the rim of the table and which are adapted to turn flattened hose into vertical position as it is coiled on the table.

The invention also comprises the improvements to be presently described and finally claimed.

In the following description reference will be made to the accompanying drawing forming part hereof and in which:

Figure 1 is a somewhat diagrammatic and schematic elevational view partly in section of a winder or reel embodying features of the invention.

Figure 2 is a top or plan view of the same; and

Figure 3 is an end view of the guide rolls and their mounting.

Referring to the drawing, 1 indicates a circular turntable mounted from underneath for rotation about a substantially vertical axis. The mounting is shown to comprise a pedestal member 2 and a carrying member 3 attached to the under

bearing 4 and a holdown 5 between these members. On top of the table there is a centrally disposed socket or keyway 6. 7 is a hand crank having a shank 8 shown as square in cross section and the shank is adapted at its end to detachably engage the keyway or socket 6 in order to rotate the table. 9 and 10 indicate a pair of oppositely disposed clamping fingers adapted to cooperate respectively with fire hose couplings of different diameters. These fingers have a common shank 11 slidably adjustably and reversibly mounted on the stem 8 of the hand-crank. 12 and 13 are a pair of aligned guide rolls of which one (12) is horizontal and the other (13) is inclined in respect to the first and they are arranged in proximity with the rim of the table and are adapted to turn the fire hose into vertical position as it is coiled on the table. 14 is a cruciform base provided with an upright frame 15 on which the guide rolls are turnably mounted. 16 The pedestal member 2 is also mounted on the base 14. The base 14 and parts carried thereby is portable and is capable of being slid into any required position.

To wind a hose it is led over the guide rolls and the coupling at its end is engaged by one or the other of the clamping fingers 9 and 10 for which purpose the clamp structure is slid upward to receive the coupling and then downward to hold it. In order to bring the appropriate clamp finger into operation with a hose end coupling the clamp structure may be slid off the lower end of the shank 8, inverted, and then the parts reassembled. By rotating the crank 7 the table is turned and the hose is coiled with its wall flatwise rather than cylindrical. The guide rolls 12 and 13 over which the hose passes ensure this result. To unwind a coiled hose the crank 7 is removed, the coil placed upon the table and its end drawn away from the table or, if desired, the crank may be present during the operation.

It will be obvious to those skilled in the art to which the invention relates that modifications may be made in details of construction and arrangement without departing from the spirit of the invention which is not limited in respect to such matters or in respect to matters of mere form or otherwise than the prior art and the appended claims may require.

I claim:

1. A hose winder comprising the combination of a turntable mounted from underneath for rotation about a substantially vertical axis, and provided on top with a centrally disposed socket, a hand crank having a shank adapted at its end

to detachably engage the socket, a clamp finger having a shank adjustably mounted on the stem of the hand crank for up and down movement and said clamp finger adapted to overlie and engage the coupling at the end of a length of hose, and a pair of aligned guide rolls of which one is horizontal and the other is inclined in respect to the first, and which are arranged in proximity with the rim of the table and are adapted to turn 10 and flatten the hose into vertical position as it is coiled on the table.

2. The combination substantially as described in claim 1 and in which there is provided a cruciform base provided with an upright frame and 15 on which base and frame the table and guide rolls are respectively mounted.

3. The combination substantially as described in claim 1 and in which there is a second clamp-

ing finger oppositely disposed in respect to the first clamping finger and said fingers adapted respectively to engage hose couplings of different diameters and the finger shank being reversibly mounted on the stem of the hand crank. 5

4. In a reel or winder for fire hose a substantially flat top table rotatable about a substantially vertical axis, means for turning the table, a clamp for clamping the coupling at the end of a length of fire hose and rotatable with the table 10 and a pair of guide rolls adjacent the rim of the table and of which one is horizontal and the other inclined and which are constructed and arranged to turn the hose edgewise into upright position as it is spirally wound on the flat top of 15 the table.
